PHONOGRAPH RECORD HOLDER

Alfons M. Rauch and Joseph M. Collyer,
Elmsford, N. Y.

Application November 10, 1948, Serial No. 149,566

Term of patent 3½ years

(Cl. D33—10)

To all whom it may concern:

Be it known that we, Alfons M. Rauch and Joseph M. Collyer, residing at Elmsford, in the county of Westchester, in the State of New York, have invented a new, original, and ornamental Design for a Phonograph Record Holder, of which the following is a specification, reference being had to the accompanying drawing, forming a part hereof.

Fig. 1 is a perspective view of a phonograph record holder, showing our new design; Fig. 2 is an end elevational view of the same.

We claim:

The ornamental design for a phonograph record holder, as shown.

ALFONS M. RAUCH.
JOSEPH M. COLLYER.
